UNITED STATES PATENT OFFICE.

HUGO LOEWE, BARTHOLOMEW VAN DAN ELZEN, AND LOUIS VAN DAN ELZEN, OF EAST ST. LOUIS, ILLINOIS.

MOLD FOR BUILDING-BLOCKS.

SPECIFICATION forming part of Letters Patent No. 768,668, dated August 30, 1904.

Application filed April 18, 1904. Serial No. 203,641. (No model.)

To all whom it may concern:

Be it known that we, HUGO LOEWE, BARTHOLOMEW VAN DAN ELZEN, and LOUIS VAN DAN ELZEN, of East St. Louis, St. Clair county, 5 Illinois, have invented certain new and useful Improvements in Molds for Building-Blocks, of which the following is a specification.

Our invention relates to sectional and changeable molds for forming building-blocks.

The objects of the invention are to provide a sectional mold which may be used in single sections or in a plurality of sections; to provide each mold in four sections hinged at their 15 corners and separably keyed at the fourth corner; to provide two sides of one mold with laterally-projecting apertured ears to receive apertured lugs on an abutting mold-section, which lugs have wedges passed through them 20 to key the whole together; to provide division-plates constructed to separate the mold-sections and be held by said lugs and wedges; to provide the inner faces of the mold-sections with removable key-forming and tongue-and- 25 groove-forming devices.

These and other objects are accomplished by the mechanism shown in the accompanying drawings, in which--

Figure 1 is a perspective of one of the mold 30 frames or sections. Fig. 2 is a side elevation of a series of the mold-frames arranged for a block of, say, five inches in thickness. Fig. 3 is a like view for a block, say, four inches thick. Fig. 4 is a plan of a partition-plate. 35 Figs. 5 and 5^a are plan and section of a bottom or end plate. Figs. 6, 7, 8, and 9 are detail views of members or sections of the molds or frames. Fig. 10 is a perspective of a block formed by our mold.

40 A designates a rectangular open mold section or frame formed of ends A' A² and sides A³ A⁴, all formed of metal plates. C C C are hinges connecting this sectional frame at three of its corners, while the fourth corner is connected by forming the end a of the section A' with a slot a', through which the reduced end a³ of side A³ is passed, the end a³ having an

aperture through which is passed a wedge D, which secures the parts firmly but separably together. Within the mold thus formed we 50 provide a removable bead or rib G to produce a corresponding groove around a molded block.

Where the blocks are to be formed, as in Fig. 10, with seats or depressions to receive 55 the ends of correspondingly-shaped blocks to form a key, we provide the key-forming plates E E', adapted to be secured to the inner faces of the mold sides A² A³ by means of the screws H, and the inner faces of these plates 60 E E' are formed, respectively, with a rib G' and a groove G² to form a groove and tongue on the blocks. The sides A² A³ and the plates E E' are further provided with transverse apertures F to receive removable dowel-pins 65 F' to form corresponding sockets in the blocks.

The sides A³ A⁴ are provided with laterally-projecting pairs of lugs B B' B' B', bolted thereto, as shown. The lugs B are at the lower edges of the sides and are provided 70 with slots b, while the lugs B' are at the upper edge of the sides and are provided with tongues b', adapted to pass up through the slots b of the lugs B on a superposed frame or mold-section, as shown in Figs. 2 and 3. 75 These tongues b' are provided with slots b², through which are passed the wedges D' to hold the mold-frames together.

I designates a partition-plate of a size to cover a mold-frame completely, and this plate 80 has four lugs i, provided with slots i', through which the tongues b' are passed. A similar plate I' forms the bottom of a mold, but in lieu of the slots i' is provided with slotted tongues i², like the tongues b', and held to 85 the lugs B of the bottom mold-sections by wedges D'.

Where but a single block is to be formed, a single mold section or frame A is used, in which case the plate I forms the top and plate 90 I' the bottom of the mold. In case a block the thickness of two mold-sections is to be formed then two mold-sections are keyed together. Where the mold is to be used for

concrete or other materials requiring pressure, the single mold above described will be used.

In using the mold-frame for casting the frames are placed vertically in a mold-box, with their ends A' uppermost and open. As soon as a mold-frame is filled its end A' is swung down and closed by its wedge D. A number of molds will be placed face to face and secured, as shown in Figs. 2 and 3. In practice as the rear mold-frame is removed a mold-frame will be added at the front of the series and filled. In opening the mold-frame it is placed on its plate A², and the plates I are then removed, and then the wedge D is removed and the frame unfolded away from the molded block, which in about five minutes is sufficiently strong to be self-sustaining in the drying-rack. Before removing the wedges D the pins F', when used, are removed, so as not to break the blocks around the holes. The beads G on the end plates A' A² are held in place by countersunk screws g, so that they may be removed when it is desired to form the ends of the blocks plain, which will be the case with blocks whose ends are exposed at the corners of buildings or other structures.

By connecting a plurality of molds of varying depth it is possible to mold blocks of different thicknesses, as shown in Fig. 2, where a block, say, five inches thick may be formed, while in Fig. 3 a block, say, four inches thick may be formed.

By this invention only two sets of individual molds are required to make various thicknesses of blocks, thereby cheapening the manufacture. As the key-plates E E' are detachable, it will only be necessary to remove one of them to form a sill or floor or ceiling block, the screw-holes being filled to insure evenness. By removing both key-plates a rectangular block may be formed. The holes F allow pins F' in mold to form holes in blocks for dowels or for inserting stiffening-rods during erecting of walls, &c. The wedges D' are formed so that they may be used for fastening plates I I' to mold-frame or plates and frame to frame, the wedges being straight on one side and inclined at the side which engages the tongue-slots.

Having thus described our invention, what we claim as new, and desire to secure by Letters Patent, is—

1. A mold comprising a separable sectional frame and pairs of laterally-projecting lugs on the side pieces independent of the means for connecting the frame members together; the lugs next to one edge of the mold having openings or slots and the other lugs having slotted or apertured tongues.

2. A mold comprising a separable sectional frame and pairs of laterally-projecting lugs on the side pieces; the lugs next to one edge

of the mold having apertures or slots and the lugs at the other edge having slotted tongues, 65 a bottom plate having slotted tongues to pass through the slotted lugs and an opposite or partition plate having slots through which the first-named tongues may be passed and wedges for all of said slotted tongues. 70

3. A mold comprising a separable frame in hinged sections; one end of one side of the frame having a slot through which a slotted end of the adjacent end piece is passed, a wedge for said slotted end, apertured lugs on 75 the lower portions of the sides of the mold, projecting slotted tongues on the upper portions of the sides of the mold, whereby a plurality of molds may be connected, plates of the same size as the molds and also having 80 slots and tongues, for use with the slots and tongues on the molds and wedges for said slotted tongues.

4. A sectional separable mold provided with front and back key-plates, one being tongued 85 and the other grooved to form bonding ribs and grooves along the blocks, and means for securing said key-plates removably in place for simultaneous or separate use.

5. A sectional separable mold provided with 90 front and back key-plates one being tongued and the other grooved to produce keys in the blocks having bonding ribs and grooves in their opposite faces.

6. A sectional separable mold provided with 95 a rib around its interior to form a groove around the molded block, and key-forming plates between the ends of two of the mold sides and having tongued and grooved edges to form bonding ribs and grooves in the opposite 100 edges of the block.

7. A sectional separable mold having a rib around its interior to form a groove around the block, key-forming plates between the ends of two of the mold sides or sections and 105 having tongued and grooved edges to form bonding ribs and grooves in the opposite edges of blocks; said sides and key-plates having openings for dowel-pins to form sockets in the blocks. 110

8. A sectional, separable mold provided around its inner walls with a rib to form a groove around the molded block, and a key-forming plate secured to the inner face of one wall of the mold to form a seat in that edge 115 of the block of a length to receive the keys formed at the abutting end portions of similarly-formed blocks.

9. A mold formed of a plurality of superposed, separable, hinged frames, the upper portions of one frame having slotted tongues and the lower portion of the next frame having slotted lugs, receiving said slotted tongues, 120 wedges passed through the slotted tongues and shaped to force the frames closely together, partition-plates slotted for the pas- 125

sage of said tongues and a bottom plate having slotted tongues for the lowermost slotted lugs.

10. A mold formed of a plurality of superposed, separable, hinged frames of varying depth, tongue-and-slot connections between the frames, wedges for said tongues, a bottom plate and partition-plates having similar slots and tongues.

In testimony whereof we affix our signatures to
in presence of two witnesses.
